UNITED STATES PATENT OFFICE.

HOWARD C. BROWN AND GEORGE WILLIAMS, OF AKRON, OHIO, ASSIGNEES OF ONE-
THIRD TO EDWARD MCSWEENEY.

PNEUMATIC-TIRE CORE.

1,192,272.

Specification of Letters Patent. Patented July 25, 1916.

Application filed December 3, 1913. Serial No. 804,449.

To all whom it may concern:

Be it known that we, HOWARD C. BROWN and GEORGE WILLIAMS, citizens of the United States, residing at Akron, in the county of 5 Summit and State of Ohio, have invented new and useful Improvements in Pneumatic-Tire Cores, of which the following is a specification.

This invention relates to means in collapsible or separable cores for use in manufacturing the outer-shoes of double tube pneumatic tires, the object of the invention being to provide a simple and inexpensive construction of sectional core in which the 10 core ring and mandrel are combined in a unitary structure, and which embodies simple and effective means for connecting the sections of the core together so that the side plates or rings and transverse fastening 15 bolts usually employed may be dispensed with, the number of parts reduced and the construction materially simplified, rendered less expensive of manufacture and time and labor saved in setting up and collapsing the 20 core.

The invention consists of the features of construction, combination and arrangement of parts herein fully described and claimed reference being had to the accompanying 25 drawing in which:—

Figure 1 is a side elevation of a collapsible core embodying our invention, showing the core set up for use. Fig. 2 is a vertical transverse section on the line 2—2 of Fig. 1. 30 Fig. 3 is a transverse section on the line 3—3 of Fig. 2. Fig. 4 is a perspective view of one of the fastening wedges.

In carrying our invention into practice, we provide a core or mandrel with the usual 35 flange 2. The core may be made of any suitable number of sections. In the present instance we have shown it as composed of three sections 3, 4 and 5, but any desired or suitable number of sections may be employed. The core may be suitably formed to produce any of the well known types of 40 tire shoes in common use. In practice, we preferably employ a core consisting of three sections, and make the key section 3 relatively smaller than the other segmental sections 4 and 5, which are of equal size, thus

enabling the parts to be more easily and conveniently handled.

The end faces of the respective core sections are adapted to abut and are provided 45 with transverse recesses 6 and intersecting grooves 7. The recesses 6 of opposing faces form a wedge-shape passage, and the grooves 7 of opposing faces are arranged to converge from one side to the opposite side 50 of the core, as shown. The sections are adapted to be held connected by locking blocks 8, which blocks are adapted for engagement with the intersecting recesses 6 when the sections of the core are brought together. The said blocks are wedge-shape to fit dove-tailed passages formed by mating recesses to bring the meeting faces of the 55 core sections in such relation that the edges and peripheral portions of said sections will exactly coincide. The block is provided upon one of its faces with ribs or projections 9 adapted to engage the groove 7 of opposing core sections, which ribs converge in accordance with the convergence of 60 said grooves to draw the core sections snugly together, thus insuring their firm engagement. The reduced end of the block is provided with a threaded stem or projection 10 which projects outwardly through the core 65 beyond the restricted end of the passage formed by recesses 6 and is adapted for engagement by a washer 11 and nut 12 to retain the block in position.

It will be seen from the foregoing description that the invention provides a core which comprises a minimum number of parts, which dispenses with the side rings and bolts commonly employed, and the sections of which may be quickly, conveniently 70 and firmly fastened together by means of the wedge blocks thereby obviating the necessity of using rings of the character described and reducing the number of manipulations required in setting up or collapsing the core, a desired simplicity thus being obtained.

We claim:—

A collapsible core comprising a series of sections, said sections being provided in 80 their opposing faces with mating recesses 85 forming wedge-shape passages and coacting

pairs of diverging grooves intersecting said passages, wedge-shape blocks adapted to be inserted in said passages and provided with convergent projections to engage said grooves, the reduced end of each block being provided with a threaded stem, and a nut adapted to engage the stem to hold the block in position.

In testimony whereof we affix our signatures in presence of two witnesses.

HOWARD C. BROWN.
GEORGE WILLIAMS.
